TYPOGRAPHICAL COMPOSING, CASTING AND DISTRIBUTING MACHINES

Louis Rossetto, Flushing, Paul Hilpman, Garden City, and William B. Abbott, Springfield Gardens, N. Y., assignors to Mergenthaler Linotype Company, a corporation of New York

Application September 9, 1950, Serial No. 184,072

10 Claims. (Cl. 199—11)

This invention relates to typographical composing, casting and distributing machines of the conventional type, such as Linotype machines of the general organization represented in the basic Mergenthaler United States Letters Patent No. 436,532, wherein matrices are released from their storage magazine in the order in which their characters are to appear in print, then composed in line, the composed line transferred to the face of a slotted mold, the mold filled with molten metal to form a type bar or slug against the matrices, and the matrices thereafter returned through distributing mechanism to the magazine from which they started.

The speed of operation of the commercial machines is normally between six to seven cycles per minute or, to express it differently, six to seven lines per minute. In recent years, there has been a growing demand for machines capable of operating at a higher speed, especially in the case of machines equipped with tape-operated keyboards.

The present invention is intended to meet this demand without departing from the basic design of existing machines. The exact manner in which this is accomplished will best be understood from the detailed description to follow, but it may be stated at this point that, as a result of the various improvements incorporated throughout the machine, the speed has been practically doubled, that is to say, increased up to twelve cycles per minute or slightly higher. While all of the improvements have been made with this high speed operation in view, nevertheless many of them would be equally useful in machines operated at normal speeds.

Referring to the drawings:

Fig. 1 is a front elevation of the complete machine;

Fig. 2 is a side elevation, looking from the right;

Fig. 3 is a side elevation similar to Fig. 2, but with some of the framework removed and certain of the parts shown in section;

Fig. 4 is a rear elevation of the magazine structure and the distributing mechanism, showing in particular the means employed for shifting the magazines;

Fig. 5 is a detail of the operating arm for the matrix feeler associated with the distributor;

Fig. 6 is a detail of the safety device which prevents the shifting of the magazines at an improper time;

Fig. 7 is a rear view of the parts shown in Fig. 6;

Fig. 8 is a front elevation of the assembling mechanism with the cover plate of the assembler entrance removed, showing the hinged mounting of the various assembling parts;

Fig. 9 is a vertical section taken on the line 9—9 of Fig. 8, showing in particular the keyboard connections for releasing matrices from the magazine in use;

Fig. 10 is a horizontal section taken on the line 10—10 of Fig. 8;

Fig. 11 is an enlarged rear elevation of the driving mechanism for the star wheel;

Fig. 12 is a section taken on the line 12—12 of Fig. 11;

Fig. 13 is a vertical section taken on the line 13—13

2

of Fig. 9, showing in particular the removable mounting of the escapement actuating reeds as well as other details;

Fig. 14 is a section taken on the line 14—14 of Fig. 3;

5 Figs. 15, 16 and 17 are detail sectional views taken on the lines 15—15, 16—16 and 17—17 of Fig. 13;

Fig. 18 is a side elevation, taken from the left of the machine, showing in particular the first elevator and its operating cam;

10 Fig. 19 is a time chart of the operation of the first elevator cam;

Fig. 20 is a side elevation, looking from the left of the machine, of the mold disk operating mechanism;

Fig. 21 is a front view of the mold disk equipped with four molds;

15 Fig. 22 is a rear elevation of the main cam shaft and the driving means therefor;

Fig. 23 is a side elevation, looking from the left of the machine, showing the second elevator and its operating cam;

20 Fig. 24 is a time chart of the second elevator cam;

Fig. 25 is an enlarged front elevation, partly in section, of the upper transfer devices which remove the composed line from the first elevator, but showing the transfer slide locked against movement;

25 Fig. 26 is a view similar to Fig. 25, but showing the transfer slide unlocked by the first elevator when the latter reaches its topmost position; and

30 Fig. 27 is a top plan view of the parts shown in Fig. 26 and disclosing in particular the overhead operation of the line resistant slide mounted in the first elevator head.

Matrix magazines and shifting mechanism (Figs. 1 to 4 and 14)

35 While the machine could be equipped with a single magazine, it is herein shown with two magazines A containing matrices X of two different fonts. These magazines are desirably of the so-called "Model 5" variety, which means that they do not carry escapements. The magazines are removably mounted upon separate base frames A¹ which conjointly constitute a shift frame which may be raised and lowered to bring either magazine into operative position. It may be noted at this point that the inclination of the magazines is seventy degrees (70°) from the horizontal, this being a steep inclination as compared to the normal inclination of about thirty-seven degrees (37°) in standard machines. By increasing the angle of inclination of the magazines, the travel of the matrices from and to the magazines will be greatly accelerated. While the travel of the matrices could be accelerated even more by arranging the magazines in a truly vertical position, such an arrangement has been found to lead to other complications and should be avoided. An angle of the order of seventy degrees (70°) has been found to give the most satisfactory results and especially when the machine is run at a speed of twelve cycles per minute.

45 Due to the steep inclination of the magazines, the right angular path in which they are shifted has been correspondingly reduced, that is to say, to twenty degrees (20°) from the horizontal, which angle is the complement of the seventy degree (70°) angle of inclination. Advantage has been taken of this reduced angle of shift by slidably suspending the shift frame at its upper end. This has been accomplished by providing the shift frame at its opposite sides with a pair of supporting plates A² (arranged at the twenty degree (20°) angle) running on rollers A³ journaled in brackets A⁴ adjustably mounted in the fixed machine frame (Figs. 3 and 14). The supporting plates A² are attached rigidly to the lower base frame and extend upwardly far enough to provide seats A⁵ for the customary pivot pins A⁶ protruding laterally from the upper base frame. Three adjustments are pro-

vided for locating the whole magazine structure in proper position (see in particular Fig. 14): First, the pivot pin seats A⁵ are adjustable by set screws A⁷ which locate the upper base frame and the magazine thereon in proper longitudinal position within the shift frame; second, the roller carrying brackets A⁴ are adjustable by set screws A⁸ which locate the shift frame as a whole in a longitudinal direction; and third, the shift frame as a whole is located in a transverse direction by set screws A⁹ carried by the brackets A⁴ and bearing against the side edges of the supporting plates A².

At its lower end, the shift frame is unsupported except for the raising and lowering mechanism which will now be described. Rotatably mounted in the fixed machine frame are two parallel rock shafts A¹⁰, one near the lower end of the shift frame and the other near the upper end thereof. Each of these rock shafts (see Figs. 3 and 4) has fastened thereto at its opposite ends crank arms A¹¹, of the same length and angularity, which are pivotally connected by links A¹² to the bottom side of the shift frame. Each of the rock shafts also has fastened thereto, at its opposite ends, further crank arms A¹³, the corresponding pair on the respective rock shafts being pivotally connected by means of long fore-and-aft links A¹⁴. It is now evident that the two crank shafts will be caused to rotate in unison in raising and lowering the shift frame and will maintain the magazines at the proper inclination in both positions of the shift frame. The rotation of the crank shafts is effected by means of a hand lever A¹⁵ fastened directly to the lower shaft and located at the front of the machine.

In order to limit the movement of the shift frame in opposite directions and to locate the selected magazine accurately in its operative position, two pairs of fixed stops, in the form of adjustable set screws A¹⁶, are provided, one at each of the four corners of the shift frame. Each pair of stops is located in a U-shaped bracket A¹⁷ attached to the fixed machine frame (Fig. 3) and arranged to be engaged by a lug A¹⁸ protruding from the lower base frame. As can be seen at once, when the shift frame is in its lower position, all four lugs A¹⁸ thereon will bank against the lower fixed stops (as in Fig. 3), whereas when the shift frame is in its upper position, all four lugs will bank against the upper fixed stops.

The shift frame is held in either of its two different positions by means of a counterbalancing spring A¹⁹ which is connected to the shift frame through the medium of a short crank shaft A²⁰ mounted in the fixed machine frame (Figs. 3 and 4). This crank shaft has two arms of equal length, one A²¹ pivotally connected to the upper end of the spring, and the other A²² pivotally connected by means of a link A²³ to a plate A²⁴ attached to the underside of the shift frame. The parts are so related that when the shift frame occupies its lower position, as shown in Fig. 3, the lifting force of the spring A¹⁹ will be overcome by the weight of the magazine structure, which thus will be allowed to settle firmly down upon the lower fixed stops A¹⁶, it being noted that at this time the crank arm A²¹ approaches the vertical and holds the counterbalancing spring near a dead center position. When, however, the shift frame is raised to its upper position, the crank arm A²¹ will be turned down to a nearly horizontal position and thus, because of the increased leverage, enable the counterbalancing spring to exert a greater lifting force and one which is sufficient to overcome the weight of the whole magazine structure and hold it firmly against the upper fixed stops A¹⁶.

The arms A²⁵ and the associated parts represent the usual attachments for removing the magazines when desired. They are, in general, similar to those shown and described in the McNamara Patent No. 1,586,316 and form no part of the present invention.

Matrix releasing devices (Figs. 9, 10, 13 and 15 to 17)

Each of the magazines A has associated therewith a bank of escapements B independently supported in the corresponding base frame A¹. These escapements, being 5 of the "Model 5" type, have actuating slides B¹ whose nose portions are arranged substantially flush with the discharge end of the magazine. Due to the steep inclination of the magazines, the actuating slides B¹ of the magazine in operative position are arranged to be engaged directly by the upper ends of a corresponding series of reeds B², whose lower ends are likewise arranged to be engaged directly by the usual power-operated key-board slides B³.

As a feature of the present invention, the actuating reeds B², instead of being mounted in the fixed machine frame, are mounted in an auxiliary rectangular supporting frame B⁴ which is detachably connected to the fixed machine frame so that the whole series of reeds may be removed as a unit. The auxiliary supporting frame B⁴ is provided with upper and lower comb plates B⁵ to guide the reeds in their upward and downward movements and also near the top with a banking bar B⁶ which supports the reeds in their downward position. Springs B⁷, attached to the lower comb plate, act to return the reeds to their lower position after they have been raised by the keyboard slides B³ to operate the matrix releasing escapements.

The detachable mounting of the reed supporting frame is best shown in Fig. 13. There it will be seen that the frame is supported at its lower end and at opposite sides by means of slotted lugs B⁸ arranged to fit over supporting studs B⁹ projecting inwardly from brackets B¹⁰ attached to the fixed machine frame. The lugs B⁸ are provided at the upper ends of their slots with adjustable set screws B¹¹ which locate the frame in a vertical direction; and the brackets B¹⁰ (see Fig. 16) are provided with adjustable set screws B¹² which locate the frame in a transverse direction. At its upper end and at opposite sides, the reed frame is provided with a pair of thumb screws B¹³ mounted in adjustable thimbles B¹⁴ on ears B¹⁵ projecting laterally from the reed frame (Fig. 15). At their rear ends, the thumb screws are threaded into sockets formed in brackets B¹⁶ projecting laterally from the fixed machine frame. As will be apparent from the drawing, 40 by loosening the thumb screws B¹³ the reed frame can be quickly detached from the brackets B¹⁶ and then lifted upwardly from the supporting studs B⁹. In restoring the frame, its slotted lugs B⁸ are lowered into place upon the supporting studs B⁹ and the thumb screws B¹³ then tightened up to attach the frame to the fixed brackets B¹⁶. The adjustable thimbles B¹⁴ serve to locate the reed frame in a facewise direction and with the reeds B² in proper vertical alignment with the escapement actuating plungers B¹.

Reverting to the power-operated keyboard slides B³, they are mounted in a separate supporting frame B¹⁷ which, as usual, is arranged to be swung from and to its operative position in the fixed machine frame. The frame B¹⁷ also contains (Fig. 9) the customary power mechanism for operating the slides B³, consisting of the pivoted cam yokes B¹⁸, the rotary cams B¹⁹ (which make one complete rotation at each matrix releasing operation), the continuously driven rolls B²⁰ for operating the cams B¹⁹, the triggers B²¹ controlling the operation of the cam yokes, and the trigger actuating slides B²². These trigger actuating slides B²² may be operated manually from the keyboard B²³ or automatically by a tape control, such as the Teletypesetter unit B²⁴ (Fig. 1). As pointed out, however, as a feature of the present invention the speed of rotation of the continuously driven rolls B²⁰ has been increased from the normal speed of about 300 R. P. M. to a higher speed of the order of 550 R. P. M. As a result, the matrices will be released at a much faster rate than 60 normally, as permitted not only by the steep inclination

of the magazines but also by reason of the greater number of cycles per minute of the rotary cams B¹⁹.

Matrix assembling mechanism (Figs. 8 to 12)

As the matrices are released from the active magazine, they fall into a vertically disposed assembler entrance C comprising, as usual, a back plate, a hinged front plate, and intermediate partition plates providing vertical channels for guiding the matrices in their fall. As the matrices issue from the entrance channels, they pass onto the upper stretch of an inclined continuously moving assembling belt C¹ passing around a lower driving pulley C² and an upper adjustable idler pulley C³. The assembling belt discharges the matrices, one by one, through a guide chute C⁴ and in front of a continuously rotating star wheel C⁵ which stacks them in line in an assembler elevator C⁶ against a yielding line resistant finger C⁷. The finger C⁷ is carried by a long slide C⁸ which is provided with a stop element C⁹ set to control the length of the line to be composed; and a double brake mechanism C¹⁰, co-operating with the slide C⁸, serves to prevent retrograde movement of the slide until the brake is released by the upward movement of the assembler elevator in forwarding the line for casting or otherwise released. These various assembling elements are conventional in form and in operation except as follows: First, the angle of inclination of the assembling belt, which normally is about forty degrees (40°) from the horizontal, has been reduced to an angle of the order of seventeen degrees forty-five minutes (17°45'); second, the linear speed of travel of the belt, which normally is about eighty-three inches (83") per second, has been increased to a speed of the order of one hundred twenty-five inches (125") per second; and third, the speed of rotation of the star wheel, which normally is about 220 R. P. M., has been increased to a speed of the order of 375 R. P. M. These changes in speed are important and all contribute to the high speed operation of the machine contemplated by this invention. Of particular interest is the fact that, while the speed of travel of the assembling belt has been increased, its angle of inclination has been substantially decreased. The purpose is to prevent matrices passing through the same entrance channel from overtaking one another while at the same time preventing transpositions of matrices passing through different channels and particularly remotely situated channels. In this connection it may be remembered that the matrices, due to the steeper inclination of the magazines and their quicker release, one after another, due to the high speed rotation of the keyboard cam rolls, pass into and through the assembler entrance at a greatly accelerated rate as compared to their normal rate of travel.

The lower pulley C² is attached to a drive shaft C¹¹ (Figs. 11 and 12) which carries a fast pulley C¹² and a loose pulley C¹³. The driving belt C¹⁴ may be shifted, in the usual way, from one pulley to the other by a belt shifter C¹⁵ operated by a hand knob C¹⁶ located at the front of the machine. Also attached to the drive shaft C¹¹ is a toothed pulley C¹⁷ which is connected by a toothed belt C¹⁸ to a larger toothed pulley C¹⁹ frictionally connected to the drive shaft C²⁰ for the star wheel C⁵, the driving ratio of the two pulleys C¹⁷ and C¹⁹ being 2 to 1. Ordinarily, the star wheel is driven by gearing on the drive shaft C¹¹, and the toothed pulley and toothed belt drive herein provided has been substituted, not only to insure the proper relative speeds of the assembling belt and of the star wheel, but also for quieter operation of the parts at the high speeds indicated. The toothed driving belt C¹⁸ is preferably made of wire reinforced rubber or rubberized fabric.

All of the assembling elements thus far described, according to the present invention, are mounted upon and carried by an auxiliary supporting frame C²¹ which is hinged at the right to the fixed machine frame for a forward swinging movement. Two hinges C²², one at the bottom and the other at the top of the frame, will suffice,

although to support the frame at the left it is provided with a lug C²³ which, in the closed position of the frame, will rest upon a shelf C²⁴ on the fixed machine frame (see Fig. 13). By being mounted on the auxiliary supporting frame C²¹, practically the entire assembling mechanism may be swung from and to its operative position at will, not only to give access to the interior parts of such mechanism, but also to give complete access to the auxiliary reed supporting frame B⁴ which consequently may be freely removed in the open position of the swinging frame C²¹. In this connection, however, it may be noted that the assembler elevator C⁶ should be raised high enough to clear the line resistant C⁷ which, like the other elements of the assembling mechanism, is carried by the frame.

The swinging frame C²¹ is held in its closed position by means of a rotary lock C²⁵ (Figs. 8 and 13) mounted on the fixed machine frame and adapted to engage in a slot formed in the end of the frame (see Fig. 11). As a safety feature, the lock is formed with an eccentric C²⁶ fitted into an elongated slot formed in the upper end of a centrally pivoted latch C²⁷. In the active position of the frame lock, and as shown in Figs. 8 and 13, the latch C²⁷ will stand clear of the assembler elevator C⁶ to permit its normal movements but if the operator attempts to turn the lock to its frame releasing position without first raising the assembler elevator, the safety latch will strike against a part of the elevator and prevent the turning of the lock. However, once the elevator has been raised clear of the line resistant finger C⁷, the safety latch is free to move and consequently will permit the turning of the frame lock for the release of the frame. In fact, such movement of the latch by the frame lock is relied upon to cause the latch to hold the assembler elevator in its raised position, it being noted that the latch by the turning of the eccentric C²⁶ will be swung to the left at its lower end and thus placed in position to intercept the downward path of the elevator. In this way, the opening of the assembling mechanism frame is prevented unless and until the assembler elevator is first moved upwardly clear of the line resistant, thus avoiding any damage to the parts. Since the safety latch maintains the elevator in its raised position, the frame is free to be swung back into place at any time so long as the frame lock remains in its frame releasing position.

It perhaps should be noted that the swinging movement of the frame C²¹ is in no way interfered with by the driving connections for the assembling belt C¹ and the star wheel C⁵. By reference to Figs. 8, 10 and 13, it will be noted that the drive belt C¹⁴, before referred to, passes over a pair of guide pulleys C²⁸ which are located immediately adjacent the axis of the hinges C²².

First elevator (Figs. 1, 18 and 19)

After a line has been composed in the assembler elevator C⁶, it is carried upward between the fingers of the line delivery carriage D and transferred through the intermediate channel D¹ into the first elevator E (Fig. 1) which thereupon descends to present the line in casting position. After casting, the first elevator is carried upward into registration with the upper transfer channel F for the removal of the line therefrom and is later restored to its original line receiving position as shown both in Figs. 1 and 18. The first elevator is slidably mounted in the vise frame G and is operated, through a long lever E¹, from a rotary cam E² mounted on the main cam shaft H of the machine. As before stated, this main cam shaft H makes one complete rotation at each cycle of operation of the machine and hence, when the machine is operated at the high speed of twelve (12) cycles per minute, the first elevator cam will impart as many complete cycles of operation to the first elevator. Because of this increased speed, the shape or contour of the cam E² has been altered to change the timing in the operation of the first elevator. This will appear from

the chart in Fig. 19 which shows two time curves, one marked OLD and the other marked NEW. By comparing these two curves, it will be observed that, whereas according to the old timing the movement of the first elevator from casting position to its upper transfer position occurred approximately in the period from two hundred degrees to two hundred forty degrees (200° to 240°) in the rotation of the cam E², such movement according to the new timing occurs approximately in the period from one hundred ninety degrees to two hundred fifty degrees (190° to 250°). This represents an increase of twenty degrees (20°) in timing for the movement of the first elevator from casting to transfer position. The comparison will also show that, whereas according to the old timing, the movement of the first elevator from its upper transfer position back to its line receiving position occurred approximately in the period from two hundred ninety degrees to three hundred twenty degrees (290° to 320°) in the rotation of the cam E², such movement according to the new timing occurs approximately in the period from two hundred eighty degrees to three hundred twenty degrees (280° to 320°), representing in this instance an increase of ten degrees (10°) in timing. These increases in timing for the operation of the first elevator have been found to be most useful in eliminating vibrations and jerky movements of the elevator when the machine is running at the high speed of twelve (12) cycles per minute. In other words, as reshaped, the cam E² imparts a comparatively slow, gradual and smooth movement to the first elevator and insures its proper alignment, both with the line delivery channel in receiving a composed line and with the upper transfer channel in discharging the line.

In allowing for more time for the movements of the first elevator, as just described, the period it remains in its upper transfer position has been correspondingly shortened, as shown by the time curves in Fig. 19. To compensate for this shortened period, certain changes have been made in the upper transfer devices as will next be described.

Upper transfer devices (Figs. 25 to 27)

The removal of the line from the first elevator E into the upper transfer channel F is effected by a pusher F¹ attached to a slide F² operated from a rotary cam on the main cam shaft H. This slide is normally locked in its leftmost position by means of the customary latch F³ (as in Fig. 25), but is unlocked by the first elevator E if and when the latter reaches its uppermost or transfer position (as in Fig. 26). The head portion of the first elevator is provided, as usual, with a U-shaped line resistant F⁴ which serves to hold the matrices upright during the movement of the elevator. Normally, the resistant F⁴ occupies a rightward position within the elevator head so that its two end portions will be engaged by the leading matrix of the line during transfer from the line delivery channel D¹ into the first elevator, the line pushing the resistant to the left as it enters the elevator. Hence, when the line is later removed from the first elevator by the pusher F¹, the line resistant must be restored to its normal position. This is ordinarily accomplished by a second pusher on the transfer slide F² which involves the use of a connecting piece extending beneath the rear wall of the first elevator head. This arrangement has been changed to provide for the operation of the line resistant from the transfer slide by means which extend above rather than below the elevator rear wall. Thus, as shown in Figs. 26 and 27, the overhead bracket F⁵ from which the pusher F¹ depends is provided with a depending hook F⁶ which is arranged to engage a strap F⁷ rising from the rear side member of the line resistant as clearly shown in Figs. 26 and 27. Consequently, in the course of transfer of the composed line from the elevator head into the upper transfer channel, the hook F⁶ will sooner or later engage the strap F⁷ and carry the line

75

resistant to the right or back to normal position. A stop pin F⁸ limits the rightward movement of the line resistant, and a friction brake F⁹ controls its leftward movement under the propelling influence of the composed line.

It is pointed out that, by operating the line resistant from above, as just described, the first elevator is free to start its downward return movement to line receiving position before the transfer slide F² has been restored to its leftmost position which is shown in Fig. 25. Since the leftward movement of the slide F² is under the control of a rotary cam on the main shaft H, the time of operation of the slide with reference to the first elevator must be taken into account.

Second elevator (Figs. 1, 23 and 24)

The normal position of the second elevator I is its upper delivery position as shown by the full lines in Figs. 1 and 23 but, at the time the matrices are shifted from the first elevator E into the upper transfer channel F, the second elevator will occupy its line receiving position as shown by the dotted lines in Fig. 23, all as well understood in the art. The movements of the second elevator are imparted to it through a system of links and levers, designated generally by the reference letter I¹, from a rotary cam I² mounted on the main cam shaft H. As in the case of the first elevator cam E², the shape or contour of the cam I² has been altered to change the timing in the operation of the second elevator. This will appear from the chart in Fig. 24 which shows two time curves, one marked "Old" and the other "New." By comparing these two curves, it will be observed that, whereas according to the old timing the movement of the second elevator from its line delivery position to its line receiving position occurred approximately in the period from two hundred degrees to two hundred fifty degrees (200° to 250°) in the rotation of the cam I², such movement according to the new timing occurs approximately in the period from one hundred seventy degrees to two hundred fifty degrees (170° to 250°). This represents an increase of thirty degrees (30°) in timing for the movement of the second elevator from line delivery to line receiving position. It has been found that this increase in timing eliminates vibrations and jerky movements of the second elevator when the machine is run at the high speed of twelve (12) cycles per minute. In other words, as reshaped, the cam I² imparts a relatively slow, gradual and smooth movement to the second elevator and insures its proper alignment with the first elevator when it is in its line receiving position. As the chart in Fig. 24 will show, no change has been made in the timing for the return movement of the second elevator from line receiving to line delivery position, the normal period allowed being satisfactory.

In allowing for more time for the movement of the second elevator from its line delivery to its line receiving position, as just described, the period it remains in its normal position has been correspondingly shortened, as shown by the chart in Fig. 24. To compensate for this shortened period, the matrix holding capacity of the distributor box J has been increased by extending its toothed bar J¹ outwardly or to the left beyond the side walls of the distributor box as shown in Fig. 1. As well understood, the matrices are transferred from the second elevator bar onto the distributor box bar by a pusher element carried by the distributor shifter slide J² which is also operated through a long lever J³ from a rotary cam on the main cam shaft H of the machine. Normally the pusher element occupies a rightward position within the distributor box and is withdrawn to the left beyond the path of movement of the second elevator at the time the latter arrives in its line delivery position or in registration with the distributor box. Immediately thereafter, the shifter slide is operated to push the line of matrices from the second elevator into the distributor box and to maintain a constant pressure on the line until all of

70

the matrices have been lifted from the box and delivered to the distributor. It can thus be seen that, because of the earlier descent of the second elevator from its line delivery position, some matrices might still be suspended from the elevator bar were it not for the extension of the distributor box bar. In other words, when the machine is run at the high speed indicated, a succession of long lines might very well cause a piling up of the matrices in the distributor box J and prevent all of the matrices on the second elevator bar from being transferred into the box at the time the second elevator starts its descent to line receiving position.

Distributing mechanism (Figs. 1 to 4 and 23)

As usual, the distributing mechanism comprises a distributor bar K and a set of rotary screws K¹ for advancing the matrices therealong. The matrices are fed, one by one, to the distributor from the distributor box J by the customary lifting finger J³⁰ (Fig. 4), this finger making one reciprocation for each rotation of the distributor screws as controlled by the cam K² on one of the distributor screws. According to the present invention, the speed of rotation of the screws K¹, which normally is about 280 R. P. M., has been increased to a speed of the order of 510 R. P. M., which means that the matrices will not only be carried along the bar at a correspondingly increased rate, but furthermore that the matrices will be fed to the bar at a correspondingly increased rate—all in keeping with the main object of the invention which is to increase the speed of the machine as a whole. The other parts of the distributor are generally the same as usual and require no specific description, such for instance as the automatic clutch K³ (Fig. 2) which arrests the rotation of the screws when a matrix becomes lodged in the distributor.

As the matrices are released from the distributor bar K, they fall into a magazine entrance L comprising, as usual, front and back plates and intermediate partition plates to provide a series of matrix guiding channels, one for each of the grooved channels in the magazine. As will be noted from Figs. 3 and 4, the channel entrance is unusually short and thus delivers the matrices into the operative magazine almost instantly as they drop from the distributor. It may also be pointed out (see again Fig. 3) that the rear or bottom wall of the magazine entrance L, for a distance equal at least to the length of an individual matrix, is straight and arranged at the same angle of inclination (seventy degrees (70°)) as the bottom plate of the operative magazine. The magazine entrance, as usual, is mounted on a swinging frame L² pivoted to the machine frame at L³ in order that the entrance may be moved rearwardly when desired to give access to the interior parts.

Mold disk and turning mechanism (Figs. 20 and 21)

The mold disk M is equipped, as usual, with four molds M¹, M², M³ and M⁴. Ordinarily, the mold disk is given one complete rotation at each cycle of operation of the machine, first, a quarter turn to carry the active mold from a vertical ejecting position to a horizontal casting position, and later to carry the active mold from the horizontal casting position back to the vertical ejecting position. Thus, under normal conditions the mold M⁴ shown in Fig. 21 would be the active mold. However, when the machine is operated at the high speed of twelve (12) cycles per minute, as herein proposed, it has been found that a single mold becomes overheated and produces a slug of poor quality. Hence, according to the present invention, the mold disk during each machine cycle is given only a one-half rotation in the two different periods in order that the two diametrically opposite molds will be brought alternately into casting position at successive operations of the machine. Thus, the mold M⁴ in Fig. 21 is the active mold and will be brought into the horizontal casting position by a one-quarter rotation of the mold disk, as normally. Later, 75

after casting, the mold disk will be given one-quarter rotation (instead of the usual three-quarter rotation) to remove the mold M⁴ from casting position and locate it in a vertical position to the left corresponding to the mold M² in Fig. 21. As a result of this one-half rotation of the mold disk M, the mold M² (diametrically opposite the mold M⁴) will be located in the vertical ejecting position corresponding to the mold M⁴ in Fig. 21. Hence, at the next operation of the machine, the mold M² will be brought into casting position for the casting of the next succeeding slug. During such second rotation of the mold disk, the previously active mold M⁴ will be located in the vertical ejecting position, as shown in Fig. 21, for the removal of the previously cast slug, which by this time has cooled sufficiently to avoid any damage in ejection. In the third operation of the machine, the mold M⁴ will again become the active mold and the sequence repeated.

The rotation of the mold disk is effected by the usual driving pinion M⁵ on a drive shaft M⁶ operated through the usual gearing M⁷ from a driven pinion M⁸. This driven pinion M⁸ is operated by two gear segments M⁹ and M¹⁰ mounted on a wheel M¹¹ (often referred to as the mold turning cam) which is secured to the main cam shaft H. The gear wheel M¹¹, as usual, makes one complete rotation at each cycle of operation of the machine, but it is pointed out that the second gear segment M¹⁰ has been made to correspond to the first gear segment M⁹, both thus being designed to impart to the mold disk two one-quarter turns at each machine cycle in the manner above described. It may be explained that the first gear segment M⁹ corresponds to the usual gear segment which effects the first one-quarter turn of the mold disk, but that the second gear segment M¹⁰ has been shortened in order to impart to the mold disk a one-quarter turn instead of the usual three-quarter turn. Both gear segments carry accelerating devices M¹² and decelerating devices M¹³ forming the subject matter of application Serial No. 174,647, filed July 19, 1950, in the name of Paul Hilpman.

When the machine is at rest, the mold disk may be adjusted to select the other pair of molds M¹ and M³ for alternate use, this being accomplished in the usual way through the drive pinion M⁵ which can be temporarily disconnected from the shaft M⁶ and rotated independently by the hand turning knob M¹⁴.

Main cam shaft (Fig. 22)

The main cam shaft, repeatedly referred to, with all of the cams mounted thereon, is shown in rear elevation in Fig. 22. The first elevator cam E², the second elevator cam I², the distributor shifter cam J³, and the mold disk turning cam M¹¹ have already been identified. The remaining cams (such as the vise closing cam, the justifying cam, the pump cam, the pot cam, the mold slide cam, the driving gear, the ejector slide cam, the line delivery and transfer cam, etc.) are conventional in form and operation and need not be described in detail, although it will be understood that, when the machine is operated at the high speed of twelve (12) cycles per minute, the various organs controlled by these remaining cams will be operated at correspondingly increased rates.

The cam shaft is driven from a variable speed motor N which is capable of rotating the shaft at a speed of from six to twelve (6 to 12) R. P. M. The motor shaft is provided with the usual driving pinion N¹ which meshes with a much larger gear wheel N² mounted on the clutch shaft which carries a small pinion (not shown) meshing with the driving gear N³ on the main shaft. The clutch, designated N⁴, controls the automatic starting and stopping of the cam shaft, which, of course, normally remains at rest.

Driving connections (Figs. 1, 3, 4, 8, 10, 13 and 22)

The driving connections for the continuously driven

parts of the machine emanate from the motor N which continuously drives the aforementioned gear N² at the proper speed. This gear N² carries a driving pulley of about the same diameter and which is connected by a belt O to a pulley O¹ on the intermediate shaft O². Near its right end, the intermediate shaft O² carries a pulley O³ which operates the driving belt C¹⁴, before mentioned, for the assembling mechanism. Still farther to the right, the intermediate shaft O² carries another pulley O⁴ which operates a drive belt O⁵ for the distributor screws. Additional pulleys on the intermediate shaft operate the drive belt O⁶ for the keyboard rollers and the drive belt O⁷ for the Teletypesetter unit (see Fig. 1).

These driving connections, except for the high speed ratios indicated, are conventional in form and in operation. It goes without saying that when the motor is operating at high speed to operate the main cam shaft at twelve (12) cycles per minute, the continuously driven parts will be operated at the high speeds already indicated. On the other hand, when the motor operates the main cam shaft at a lower speed, say the lowest speed of six (6) cycles per minute, the continuously driven parts will be operated at correspondingly reduced speeds, which reduced speeds will approximate the normal speeds also previously indicated.

Matrix feelers and safety locks (Figs. 1, 2, 3, 4, 5, 6 and 7)

The machine is equipped, as usual, with a lower matrix feeler P¹ arranged to be moved across the lower or discharge end of the active magazine to detect the presence of any matrices protruding therefrom and with an upper matrix feeler P² arranged to be moved across the path of matrices traveling along the distributor bar to detect the presence of any such matrices. Both feelers are operated in unison from a common hand lever P³ located at the front of the machine. This hand lever is fast to a shaft P⁴ having a crank arm P⁵ connected to a centrally pivoted lever P⁶ which in turn is connected by links P⁷ to the lower matrix feeler P¹. The centrally pivoted lever P⁶ is also connected by a long link P⁸ to a swinging arm P⁹ pivoted at P¹⁰ in the fixed machine frame and carrying a locking latch P¹¹ (see in particular Figs. 6 and 7). Extending laterally from the arm P⁹ is a plate P¹² giving support to a block P¹³ to which is pinned a long vertical rod P¹⁴ extending upwardly to make connection with the upper matrix feeler P². The feeler P² is carried by a pivoted arm P¹⁵ acted upon by a bell crank lever P¹⁶, whose horizontal arm is connected at its rear extremity to the upper end of the rod P¹⁴ (see in particular Fig. 5). A spring P¹⁷, connected at its lower end to the plate P¹², and at its upper end to a collar P¹⁸ pinned to the rod P¹⁴, serves normally to hold the block P¹³ down into contact with the plate P¹². The locking latch P¹¹ cooperates with an arm P¹⁹ depending from the rock shaft A¹⁰ and carrying adjustable set screws P²⁰ for contact with the locking latch.

According to the foregoing arrangement, when the hand lever P³ is depressed, the two matrix feelers, through the connections described, will be moved across the matrix paths, provided, of course, no matrices are in their way. Under such conditions the locking latch P¹¹ will be lowered out of engagement with the arm P¹⁹ and permit the magazines to be raised or lowered by the operation of the magazine shifting lever A¹⁵. In this connection it may be noted that the arm P¹⁹ occupies two different positions, the one shown in Fig. 6 being that which corresponds to the raised position of the magazine shift frame. In the lowered position of the shift frame the arm will be shifted to the dotted line position shown in Fig. 6 and the latch P¹¹ will stand in front of the arm, as also indicated by the dotted lines in Fig. 6. If any matrix is in the path of either matrix feeler P¹ or P², the locking latch P¹¹ cannot be lowered from engagement with the arm P¹⁹ and hence the magazines will be locked against shifting, whether they occupy a raised position or a low-

ered position. Under such circumstances, however, in order to prevent damage to the matrices, an auxiliary lock is provided to prevent undue pressure being brought to bear against the matrices. This auxiliary lock consists of a plate P²¹ attached to the fixed machine frame, as at P²² (see Fig. 7), and is designed to engage in a beveled notch P²³ formed in the rear side of the block P¹³. Hence, if the downward movement of the rod P¹⁴ is resisted by a matrix undergoing distribution, the spring P¹⁷ will yield and the block P¹³ (being slidably mounted on the plate P¹² carried by the arm P⁹) will be shifted rearwardly to effect the engagement of the notch P²³ with the auxiliary locking plate P²¹. In this way the locking latch P¹¹ will be prevented positively from being operated by the hand lever P³ to unlock the magazines, avoiding any damage to the parts.

As another safety feature, means are provided to depress any of the escapement reeds B² in the event that they become lodged in their upper escapement operating position at a time when an attempt is made to raise or lower the magazines. This is accomplished by the use of a depressor bar Q fast to the rock shaft P⁴ to which the hand lever P³ is connected. Hence, each time the hand lever P³ is depressed, it will operate the depressor bar and restore any raised escapement reed to its proper position. The depressor bar Q acts upon a plate Q¹ supported in the reed frame and which, when the depressor bar is operated, engages the lower walls of notches Q² formed in the reeds B². Normally the plate Q¹ is held in its uppermost position by springs Q³, also carried by the reed frame, stops Q⁴ likewise carried by the reed frame serving to limit the upward movement of the plate Q¹.

Conclusion

The various improvements have been shown and described in preferred form and merely by way of example, and obviously many variations and modifications may be made without departing from the spirit of the invention. It is to be understood, therefore, that the invention is not to be limited to any specific form or arrangement except insofar as such limitations are specified in the appended claims.

What is claimed is:

1. A typographical composing, casting and distributing machine equipped with a main shaft and provided with a series of cams controlling the operation of various organs of the machine and adapted to make one complete rotation at each cycle of operation of the machine, means for driving said main cam shaft at a rate of speed of the order of twelve cycles per minute, a series of rotary cams for operating matrix releasing devices and adapted to make one complete rotation at each matrix releasing operation, a continuously rotating roll for operating said cams, means for driving the roll at a rate of speed of the order of 550 R. P. M., a continuously moving assembling belt to receive the matrices as they are released from their storage magazine and deliver them to the assembler, means for operating said belt at a rate of speed of the order of 125" per second, a continuously rotating star wheel located beyond the assembling belt to act upon the matrices as they issue therefrom and stack them in the assembler, means for rotating the star wheel at a rate of speed of the order of 375 R. P. M., a distributor comprising a set of continuously rotating screws for advancing the matrices along the distributor bar for return to their storage magazine, and means for rotating the distributor screws at a rate of speed of the order of 510 R. P. M.

2. A typographical composing, casting and distributing machine according to claim 1, wherein the magazine in which the matrices are stored is arranged at an inclination of the order of 70°.

3. A typographical composing, casting and distributing machine according to claim 1, wherein the assembling belt

is arranged at an inclination of the order of 17° 45 minutes.

4. A typographical composing and distributing machine according to claim 1, wherein the magazine in which the matrices are stored is arranged at an inclination of the order of 70°, and wherein the assembling belt is arranged at an inclination of the order of 17° 45 minutes.

5. In a typographical casting machine, the combination of a main shaft provided with a series of cams controlling the operation of various organs of the machine and adapted to make one complete rotation at each cycle of operation of the machine, means for driving said main cam shaft at a rate of speed substantially in excess of seven cycles per minute in order to cast slugs at a corresponding rate, a rotatable mold disk provided with two identical molds disposed diametrically opposite thereon, and means operated from the main cam shaft for imparting to the mold disk two one-quarter turns in each machine cycle whereby the molds are brought alternately into casting position in successive machine cycles to avoid overheating of the molds as a result of the increased rate of speed in the casting of successive slugs.

6. In a typographical distributing machine equipped with a main shaft provided with a series of cams controlling the operation of various organs of the machine and adapted to make one complete rotation for each cycle of operation of the machine, the combination of means for driving said main shaft at a rate of speed substantially in excess of seven cycles per minute, a second elevator movable downwardly from its matrix delivery position to its matrix receiving position and return, and means for effecting such movements of the second elevator in each cycle of operation of the machine, said means comprising a rotary cam mounted on the main shaft and adapted to make one complete rotation in each machine cycle, said cam being shaped to effect the downward movement of the elevator in the period from 170° to 250° in the rotation of the cam.

7. In a typographical distributing machine equipped with a main shaft provided with a series of cams controlling the operation of various organs of the machine and adapted to make one complete rotation for each cycle of operation of the machine, the combination of means for driving said main shaft at a rate of speed substantially in excess of seven cycles per minute, a first elevator movable downwardly from its line receiving position to casting position, then upwardly to its line delivery position, and then downwardly back to its line receiving position, and means for effecting such movements of the first elevator in each machine cycle, said means comprising

a rotary cam mounted on the main shaft and adapted to make one complete rotation in each machine cycle, said cam being shaped to effect the upward movement of the elevator in the period from 190° to 250° in the rotation of the cam and to effect the downward movement of the elevator in the period from 280° to 320° in the rotation of the cam.

8. In a typographical composing machine, the combination of a matrix storage magazine arranged at an inclination of the order of 70°, an assembling belt to receive the matrices as they are released from their storage magazine and deliver them to the assembler, the angle of inclination of said belt being of the order of 17° 45 minutes, and means for driving the assembling belt at a rate of speed of the order of 125" per second.

9. The combination according to claim 8, including a series of rotary cams for controlling the release of the matrices from the magazine and adapted to make one complete rotation at each matrix releasing operation, a continuously rotating roll for operating said cams, and means for driving the roll at a rate of speed of the order of 550 R. P. M.

10. The combination according to claim 9, including a continuously rotating star wheel for receiving the released matrices from the assembling belt and stacking them in the assembler, and means for driving the star wheel at a rate of speed of the order of 375 R. P. M.
